UNITED STATES PATENT OFFICE.

AVERY C. BRUCE, OF BIRMINGHAM, ALABAMA, ASSIGNOR TO SENN PRESSED STEEL HOE & TOOL COMPANY, OF BIRMINGHAM, ALABAMA, A CORPORATION.

DESIGN FOR A RAKE.

47,021.

Specification for Design.

Patented Mar. 2, 1915.

Application filed November 10, 1914. Serial No. 871,408. Term of patent 14 years.

To all whom it may concern:

Be it known that I, AVERY C. BRUCE, a citizen of the United States of America, residing at Birmingham, in the county of Jefferson and State of Alabama, have invented a new, original, and ornamental Design for Rakes, of which the following is a specification, reference being had to the accompanying drawings, forming a part thereof.

The figure is a perspective view of a rake showing my new design, the same consisting of a rake having a reinforced neck and a handle socket formed from an integral blank which is provided with a deep vertical depression or corrugation extending from the front end of the socket across the reinforced

neck into the head of the rake, the corrugation merging into a transverse corrugation which extends across the head of the rake. The rake teeth are also provided with vertical corrugations which merge into the corrugation in the head.

I claim:

The ornamental design for a rake substantially as shown and described.

In testimony whereof I affix my signature in the presence of two witnesses.

AVERY C. BRUCE.

Witnesses:

R. D. JOHNSTON, JR.,
NOMIE WELSH.
